INVENTOR:
GEORGE W. NEWMAN

BY Lawrence C. Kingsland
ATTORNEY.

UNITED STATES PATENT OFFICE

2,196,023

BOOKBINDER

George W. Newman, St. Louis, Mo.

Application December 13, 1937, Serial No. 179,381

Renewed February 21, 1940

7 Claims. (Cl. 129—41)

The present invention relates generally to bookbinders, and is more particularly directed to novel end cap assemblages for the cases forming the foundation of the bookbinder.

5 An object of the invention is to provide a novel device for closing the ends of the cases of bookbinders.

Another object is to provide a novel cap assemblage for closing the ends of the cases of bookbinders.

10 Another object is to provide a novel cap assemblage for closing the ends of the cases of bookbinders which includes a novel securing means for maintaining the cap assemblage in

15 closing position.

Another object is to provide a novel cap assemblage for closing the ends of the cases of bookbinders including a wedge and a yoke member for securing the cap assemblage in closing

20 position.

Another object is to provide a novel cap assemblage which is adapted to be readily disposed in its closing position in the end of a case of a bookbinder.

25 Another object is to provide a novel cap assemblage which is readily manufactured, which is inexpensive, and which is adapted to be readily placed in operative disposition.

Other objects and advantages will be apparent

30 from the following description, taken in conjunction with the accompanying drawing, in which:

Fig. 1 is a plan view of a binder incorporating a preferred embodiment of the present invention;

35 Fig. 2 is an enlarged end view of the binder shown in Fig. 1, a portion being broken away for conservation of space;

Fig. 3 is a central section through an end of one case of the binder showing a preferred embodiment of the present invention in operative disposition relative to said case, certain portions being broken away;

Fig. 4 is an enlarged section on the line 4—4 of Fig. 3;

45 Fig. 5 is a section on the line 5—5 of Fig. 4;

Fig. 6 is an enlarged plan view of a yoke member forming a part of the present cap assemblage; and,

Fig. 7 is a section similar to Fig. 4 showing the

50 relation of the wedge, yoke member, cap, and case prior to driving the wedge home.

Referring to the drawing more particularly by reference numerals, 10 indicates generally a bookbinder which includes a top cover 11, a bot-

5 tom cover 12, an upper case 13, a lower case 14, Sheets 17 are disposed between the respective upper and lower elements and are maintained in such relation by appropriate mechanism disposed within the cases 13 and 14. This mechanism is shown in greater detail in my copending application Serial No. 180,129, filed December 16, 1937, such mechanism forming no part of the invention claimed in the present application.

A cap assemblage generally designated 20 is disposed in each end of each of the cases 13 and 14. The cap assemblage 20 includes a cap 21, 15 which has a curved upper section 22 of a longitudinal contour shown in Fig. 3 and of a transverse contour shown in Fig. 4. The cap 21 also includes a skirt 23, which is inwardly offset from the curved upper section 22 by a peripheral shoulder 24. The skirt 23 includes opposed slots 25 in the longitudinal sides. The curved upper section 22 includes an aperture 26.

20 A yoke member 30 and a wedge 31 comprise means for maintaining the cap 20 in place in the end of the case 13. The yoke member 30 includes end sections 32 and 33 (Fig. 6) which are disposed in a common plane and which are of a configuration to fit snugly the curved ends of the skirt 23. Between the end sections 32 and 33 is a yoke section 34 comprising identical strips 35 and 36, which include lateral projections 37 and 38, respectively, offset from the respective strips by the shoulders 39 and 40.

25 With the cap assemblage in operative disposition (Fig. 4) in the end of the casing 13, the projections 37 and 38 extend through the slots 25 and into slots 41 in the longitudinal walls of the case 13, so that the ends of the projections 37 and 38 are flush with the external surface of 30 the case 13. In some instances the projections 37 and 38 are welded in place. The shoulders 39 and 40 abut the inner surface of the skirt 23. The wedge 31 is disposed between the strips 35 and 36 in spreading relation thereto with its 35 convex blunt end 42 flush with the outer surface of the curved end section 22. The shoulder 40 of the cap 21 abuts the end of the case 13.

35 When the present cap assemblage is employed as a closure for a case housing a mechanism 50 adapted to be turned by a key insertable through the end of the cap, suitable apertures 43 and 44 are provided in the cap 21 and the yoke member 30, respectively, these apertures, of course, being disposed in aligned relation with each other and 55

with the rotatable mechanism. In some instances, it is desirable to construct one of the sections 32 and 33 of greater depth than the other in order to provide room for an aperture 5 44 disposed more centrally than as shown in Fig. 6. The resultant shifting of the yoke section 34 one way or the other and the consequent shifting of the aperture 26 is, of course, a matter of mechanical detail.

10 The installation of the cap assemblage is as follows:

The yoke member 30 is disposed within the cap 21 in a position so that the projections 37 and 38 are opposite the slots 25. The wedge 31 is 15 inserted through the aperture 26 and is moved inwardly until the wedging portion engages and spreads the strips 35 and 36 sufficiently to move the projections 37 and 38 into the slots 25 to positions flush with the exterior of the skirt 23 (Fig. 7.) The cap assemblage 20 is then disposed 20 in the end of the case 13 with the shoulder 24 engaging the end thereof. The wedge 31 is driven downwardly until it assumes the position shown in Fig. 4 which further spreads the strips 35 and 25 36, thereby moving the projections 37 and 38 into the slots 41 and into flush relation with the exterior of the case 13. It is, therefore, evident that the casing 13 is closed in a positive manner so that the cap assemblage cannot be accidentally 30 displaced and lost. Further, the cap assemblage 20 merges smoothly with the case 13 presenting no sharp corners and no obstructions.

A cap assemblage has been provided which fulfills all of the objects and advantages sought 35 therefor. It is to be understood, of course, that the several elements of the cap assemblage are constructed of material suitable for such elements, the yoke section 34 of the yoke member 30 being of a resilient material in order to expedite dismantling of the cap assemblage 20.

40 It is to be understood that the foregoing description and accompanying drawing have been given by way of illustration and example and not for purposes of limitation, the invention being limited only by the claims which follow.

45 What is claimed is:

1. In a device of the kind described, a cap, and means for maintaining said cap in operative disposition relative to a bookbinder case includ-

ing a yoke member positively engaging the cap and the case.

2. In a device of the kind described, a cap, and means for maintaining said cap in operative disposition relative to a bookbinder case includ- 5 ing a yoke member having opposed projections, and a wedge maintaining said opposed projections in engaging relation with the cap and the case.

3. A cap assemblage for closing an end of a 10 case of a bookbinder comprising a cap having aligned slots in opposed sides, a yoke member having movable oppositely disposed projections, and a wedge, said wedge being adapted to move said projections into said aligned slots. 15

4. In a device of the kind described, a case having aligned slots in opposed sides forming a part of a bookbinder, and a cap assemblage disposed in closing relation in an end of the case, said cap assemblage comprising a cap having 20 aligned slots in opposed sides, a yoke member having oppositely disposed projections, and a wedge, said projections being disposed in said slots of said cap and said case and being maintained therein by said wedge, thereby positively 25 locking said cap assemblage in closing relation with said case.

5. A cap assemblage for closing an end of a case of a bookbinder comprising a cap, a member disposed within said cap, and means for moving 30 said member into securing engagement with a case end to hold said assemblage in operative disposition relative to such case.

6. In a device of the kind described, a case forming a part of a bookbinder, a cap assemblage 35 disposed in closing relation in an end of the case comprising a cap, a member disposed within said cap in securing engagement with said cap and said case, and a second member engaging said member and maintaining it in securing engagement. 40

7. A cap assemblage for closing an end of a case of a bookbinder comprising a cap, a first member within the cap including spaced portions, and a second member within the cap in 45 engagement with the spaced portions maintaining said first member in a position locking the cap to the end of the case of a bookbinder.

GEORGE W. NEWMAN.
